UNITED STATES PATENT OFFICE

CARL E. MAHR, OF ROOT, NEW YORK

GAME

Application filed December 12, 1929. Serial No. 413,612.

This invention relates to a game and particularly a game which is capable of being played indoors and which will provide a high degree of fascination and amusement while at the same time requiring a certain amount of skill upon the part of the player or players.

A main object of the game is to provide a new and improved game board upon which a series of counters may be disposed and which are to be displaced by the players by means of projectiles.

A further object of the invention is to provide a game which is competitive and which is capable of retaining the interest of the players for considerable periods of time.

With these and other objects which will become apparent from the detailed description which follows, the invention consists in the combination and arrangement of elements below set forth, claimed in the claims appended hereto and shown in the drawings, in which

Figure 1 is a plan view of the game board with certain of the counters removed from the depressions therefor in order to show the construction of the depressions more clearly,

Figure 2 is a sectional view upon the line 30 2—2 of Figure 1,

Figure 3 illustrates in plan view a receptacle with the counters therein,

Figure 4 is a plan view of the receptacle with the projectiles, and

Figure 5 is a cross-sectional view upon line 35 5—5 of Figure 4.

Referring to the drawings in which like reference characters refer to like parts throughout the various views, 5 indicates the base of a game board which is preferably rectangular in shape and flat so as to rest upon any horizontal surface, and 6, 7 and 8 are the sides of the game board 5 raised above the upper surface of said game board so as to form a boundary about three sides of the game board to confine the counters and projectiles upon the top surface of the game board. The side 9 of the game board is open and the projectiles are projected from this end of the game board toward the counters 10 disposed

in the recesses 11 which are located in any desired arrangement within the circle 12 drawn upon the game board in the position indicated.

One of the counters 10 is of slightly larger size as shown at 14 and the counter 14 is intended to be placed at the central recess 11 as shown in Figure 1.

Upon the game board in the further corners thereof are provided two pockets 15 which are marked "Player Out" and in the center of the game board directly in back of the circle 12 is provided another pocket 16 which is marked "Game Hole."

The projectiles used are shown at 17 in Figure 4 while 18 indicates a receptacle for the counters 10 and 14 when the counters are not in use and 19 indicates a receptacle for the projectiles 17 when not in use.

The recesses 11 are constructed in a peculiar way shown more particularly in Figure 2 and they consist of a counter-sunk portion 20 in the game board itself which is preferably made of wood and in the counter-sunk portion 20 is placed a cup-shaped receptacle 21 having the flanges 22 thereon adapted to rest upon the top surface of the game board. The receptacle 21 is secured to the game board itself by means of a screw or other fastening means 23. The counters are preferably ordinary marbles, but it is of course obvious that metal spheres or spheres of other construction can likewise be used in place of the marbles. The projectiles 17 are also preferably marbles which are of a contrasting color from the counter marbles.

The game is played as follows:

The various recesses 11 have assigned thereto a certain predetermined value, such as 5, shown within the circle in Figure 1, while the central recess preferably has the value 20 assigned thereto as shown. The game hole has assigned thereto a value of 100, as shown. It is of course apparent that any other values desired may be assigned to these various recesses and pockets. The player takes the projectiles 17 and projects them from the side 9 of the game board 5 toward the counters 10 and 14 which are all in place upon the various recesses provided

within the circle and endeavors to displace as many as possible without at the same time directing the projectile itself into either one of the pockets 15 which would automatically 5 retire the player from the game. If any counters drop into the pocket 16, such counters would count 100 towards the game total while any counters displaced from the recesses and moved outside of the circle 12 10 will count either 5 or 20 depending upon the recess from which they are moved toward the game total. It is necessary that the counters be displaced out of the circle 12 in addition to being displaced out of the recess 15 itself in order to count toward the game total.

The purpose of the flanges 22 upon the receptacles 21 becomes apparent since these flanges prevent the re-entry as a usual thing 20 of a counter into a recess after it has once been displaced from a recess. In the game described, the game total is preferably placed at 200.

When any number of players up to four 25 are competing in the game, then each player projects all four projectiles unless he is automatically retired from the game by one of the projectiles rolling into a "Player Out" hole, and after such player has rolled his 30 four projectiles then the board is rearranged again with all the counters in place and the next player projects the four projectiles. If more than four players are competing, then it is generally more satisfactory and 35 more interesting if each player only projects two projectiles.

The player who first scores 200 of course 40 wins the game, or if more than one player has scored 200 then the one with the largest total scored will be the winner.

From the above description it is apparent 45 that a very interesting and fascinating indoor game has been devised which will furnish amusement and interest to a plurality of players, but it is also apparent that various modifications may be made in the structure 50 of the game board itself as well as the rules for playing the game without departing from the spirit of the invention, and it is my intention to include all such modifications and 55 changes as will fall within the spirit and scope of the following claim.

I claim:

A game board of rectangular configuration, 55 a raised border upon three sides thereof allowing projectiles to be projected at the other side, a series of recesses in said game board located within a circular border, receptacles located in said recesses for counters, flanges upon said receptacles resting 60 upon the surface of said game board to prevent accidental reentry of said counters into said receptacles when said counters have been displaced therefrom, a series of hazard 65 pockets in said game board located outside

said circular border and a target pocket also located outside said circular border.

In testimony whereof I have signed my name to this specification.

CARL E. MAHR.
